UNITED STATES PATENT OFFICE.

JOHN STEMBER, OF NEW YORK, N. Y.

DESIGN FOR A BELT.

SPECIFICATION forming part of Design No. 35,438, dated December 10, 1901.

Application filed November 14, 1901. Serial No. 82,324. Term of patent 3½ years.

To all whom it may concern:

Be it known that I, JOHN STEMBER, a citizen of the United States, residing in the borough of Manhattan, city, county, and State of New York, have invented and produced a new and original Design for Belts, of which the following is a specification.

My invention relates to a design for belts.

I will describe a belt embodying my invention and then point out the novel features thereof in a claim.

The accompanying drawing illustrates in elevation a belt embodying my invention.

A represents the body of the belt, having at one end a buckle A' and provided with eyelets A² at its other end. The lower edge a of the body is a compound curve, and the upper edge a' at the end portions of the body approximately conforms to that portion of the lower edge immediately beneath it.

At about the middle of the belt is a comparatively high point B, the sides b of which are concave curves which continue into the curve of the upper edge. The continuation of the sides into the curve of the upper edge 25 produces raised portions b'.

The surface at the middle of the belt is decorated with three shields, the outlines of which are made by scrolls, as shown.

The leading or essential features of my design are the ornamented middle portion of the belt and the curvature of the upper and lower edges of the belt. 30

Having thus described my invention, what I claim as new, and desire to secure by Letters 35 Patent, is—

The design for a belt, as herein shown and described.

In testimony whereof I have signed my name to this specification in the presence of 40 two subscribing witnesses.

JOHN STEMBER.
